UNITED STATES PATENT OFFICE.

GEORGE B. SCHEFFEY, OF NORWICH, CONNECTICUT, ASSIGNOR TO LIGHTSHIP BOARD COMPANY, INC., OF WEEHAWKEN, NEW JERSEY, A CORPORATION OF NEW JERSEY.

CLOTH BOARD OR SIMILAR ARTICLE.

Application filed June 15, 1925. Serial No. 37,128.

My invention relates to cloth boards or similar articles used mainly as centers upon which various fabrics are wound.

The general object of the invention is to provide an improved board of the class frequently identified as "flapper boards", which are of substantially hollow construction, usually consisting of a wooden frame and a fabric or paper cover. The wooden frames 10 are unduly expensive, especially in recent years, because of the increase in cost of lumber, and while evidently lighter than a solid wood board of the same thickness, they have a considerable weight which materially affects the cost of shipment of the boards either to the textile mill, or from the mill 15 to the consumer in bolt form.

By study and experiment I have found that an improved cloth board of this type 20 can be made with a frame of materials of the class broadly referred to as paper instead of wood, with a great saving in cost of material while possessing substantially as much strength or more strength than 25 wooden frames, unless the latter are very carefully made. In carrying out the invention as exemplified in the specific structure chosen for illustration, not only is the completed cloth board substantially hollow in 30 the sense above mentioned, but the individual members constituting the frame are themselves hollow or tubular in order to provide great strength and rigidity, with very light weight and a minimum amount 35 of material and therefore at very low cost. The material used is preferably a cheap grade of paper stock or pulp and it may be specifically of the classes known as straw-board or pulpboard, suitably formed and secured together as described hereafter. While 40 this economical material has not a high finish or especially attractive appearance, these items are insignificant because the frame parts are, in preferred cases, entirely concealed by cover or envelope materials.

The frame structure is also devised so that, without regard to the specific material employed, it is very strong and rigid in proportion to the weight or cross sectional area 50 of the members, and especially the end members have portions which overlap the ends of the side members to resist inward displacement of the end members and to provide smooth, flat outer end faces of the frame which have an area equal to the full

width and thickness of the frame and so provide proper bases to receive and maintain necessary end labels in proper condition during the life of the frame and cloth board or of the fabric bolt in which the board is 60 used as a core. Other structural features of the frame are fully explained in the detail description.

The characteristics and advantages of the invention are further sufficiently described 65 in connection with a detail description of the accompanying drawing, which shows certain exemplifying embodiments of the invention. After considering these, persons skilled in the art will understand that many 70 variations may be made within the principles of the invention, and I contemplate the employment of any structures that are properly within the scope of the appended claims.

Fig. 1 is a perspective view of a cloth 75 board embodying the invention in one form.

Fig. 2 is a perspective view of the frame with a part broken away, in position upon a sheet of envelope or cover material which is ready to be folded and secured upon the 80 frame.

Fig. 3 is a section at 3—3, Fig. 1.

Figs. 4 and 5 are perspective views of frame details.

The frame comprises the longitudinal or 85 side members S, end members E, and preferably one or more transverse members, which are conveniently called braces, B. Each of the frame members, for reasons above stated, is preferably hollow or tubular, but the forms of various members preferably differ. Thus, the side members S are more desirably of cylindrical form and the transverse members, including E and B, are desirably of polygonal or rectangular 90 cross-section.

The side members S may conveniently consist of ordinary commercial tubing formed from spirally rolled strips of straw-board or other sufficiently cheap material of the same general class. These tubes are available in the general market and their use avoids manufacturing cost other than cutting to proper lengths. They are also desirable because they provide, without further attention or treatment, the desired rounded longitudinal edges of the completed boards.

The transverse members are desirably of 110 polygonal cross-section, not only because

this structure provides desirable flat outer surfaces for contact with the envelope material, but because polygonal members are more easily shaped for secure fastening to the cylindrical side members, as will appear.

The braces B may each be formed from a single sheet 1 of fibrous sheet material of suitable grade with due regard to economy, and of substantial thickness and stiffness for the necessary structural strength. Specifically, in one preferred form, I have made the transverse members, including braces B of a fairly cheap grade of pulp board. The blank is scored or creased along the lines 2 to facilitate bending, and is then bent into rectangular tubular form, as sufficiently shown in Fig. 2. One longitudinal portion or flap, such as 3, overlaps another, such as 4, and these are adhesively secured together to form a strong and unitary tubular frame member. Before or after the blank is folded and secured in tubular form, part-circular cuts are made in its ends, producing the arcuate formations 5, which are so arranged that when the blank is folded into tube form these curvatures are at opposite sides of the tube ends, and the entire tube end is thus shaped to accurately fit the curvature of the side member, against which it is placed and adhesively secured in a manner which is obvious in Fig. 2. A detail of advantage consists in so arranging the blank portions having the cuts 5, that they are preferably made in the overlapping members 3 and 4 as well as one of the other blank portions 6. In this way the greatest area of end surfaces of these members is provided for adhesive attachment to the side members.

The end frame members E may desirably be made in two or more parts, securely fastened together as explained below. One principal part 10 of each end member may desirably be substantially identical with the cross braces previously described, although evidently dimensions may be varied as necessary or desirable. Against an outer face of this portion 10 is laid and adhesively secured another main outer portion 11 (Fig. 5) which may itself be composed of a plurality of layers or plies 12 of fibrous sheet material, usually a pulp board of the same grade and thickness as the blanks 1. Of course in some cases a single ply outer member 11 may be used, but a multiple structure is generally preferred, in order to give great stiffness and strength to the board ends. Usually the outer members 11 are glued to the sides of the tubular members 10 which consist of the overlapped blank portions 3 and 4 in order to provide the greatest available strength and stiffness at points as near as possible to the board ends.

The members 11 project beyond the ends of members 10 and overlap the ends of the side members, and are formed with rounded

ends 13 to conform to adjacent outer surface contours of the side members. In brief these outer members 11 are dimensioned in conformity with the end outline of the completed board, as easily understood in Figs. 70 1 and 2, and the rounded ends 13, of course, conform to the curvature of the side tubes which they overlap. A complete end member consisting of portions 10 and 11 may be secured together and used as a unit in building up the frame structure, or the separate members may be positioned and secured independently.

When cloth boards are placed in winding machines to wind fabric upon them the 80 chucks of the winding machine impose heavy end pressure on the board ends tending to displace the end members inwardly unless the end members are properly designed and securely held against such displacement. In 85 the present structure the formation of the end members 10—11 with end portions fully overlapping the ends of the side members S provides for the transfer of this winding 90 chuck pressure directly to the side members without possibility of displacing the end members inwardly. Shoulders of substantial area are also formed at the ends of the end members adjacent the portions thereof which overlap the ends of the side members. 95 These shoulders engage and conform to the inner contours of the side members and provide ample contact and bracing effect to resist angular distortion of the frame. Also the formation of the end members with their 100 end portions overlapping the ends of the side members, provides smooth, flat outer faces which cover the full areas of the board ends without any joint or other interruption, and these areas are therefore admirably 105 adapted for the proper reception and retention of the necessary end or finishing labels in proper condition during the life of the cloth board or the fabric bolt in which it is used as a core. The ends of the overlapping 110 portions of the end faces are also conformed in accordance with the outer edge contours of the side members so that the board edges from end to end are smooth and straight, and provide an uninterrupted smoothly 115 rounded surface for the fabric, edge margins of which overlap the ends of the board end pieces 11. In the finished bolt the end labels applied to the outer faces of the end members 11 are practically flush with the 120 aligned edges of the fabric wound upon the board.

For the sake of attractive appearance and to form a smooth and uninterrupted outer surface upon which fabrics of any description may be wound without injury, the frame is usually covered. Any suitable fabric or fibrous sheet material may be used for this purpose, but preferably the cover or envelope C, Figs. 1 and 2, consists of fibrous 130

sheet material of substantial thickness and strength for the purpose in view, although usually not nearly so thick as the sheet material composing the frame members. In 5 brief, a suitable envelope material is a fairly good grade of wrapping paper, which need not be very heavy or expensive, since the main purpose of the envelop is to cover and seal the frame and provide an unbroken surface in the completed board; although, of course, where the cover material has any 10 very substantial tensile strength it serves to materially reinforce and strengthen the completed structure.

15 The envelope may be glued before or during its application to the frame, and for convenience in factory production methods, one entire surface of the sheet may be glued as indicated by stippling in Fig. 2. This is 20 especially convenient where automatic or partially automatic gluing machines are provided, and which, in many cases, are arranged to glue entire sheet surfaces and advance them to a point of utilization. When 25 the sheets are thus glued over their entire surfaces, that operation, of course, automatically provides for the adhesion of the sheets to frame members wherever it overlies them, and also for securing the overlapped longitudinal sheet margin, such as 15. When so 30 glued, the adhesive tends to materially reinforce and strengthen the sheet at points where it is not in contact with frame members.

35 Otherwise, glue may be applied only to certain areas of the envelope that are to be brought in contact with frame members, in addition to the flap portion 15. Thus glue may, when desired, be applied to longitudinal areas corresponding to the areas of contact with the side frame members S. The envelope is applied and folded about the frame in an obvious way and secured by pressure, care being taken to stretch the 45 sheet smoothly and tightly.

Usually the main envelope sheet is only long enough to cover the sides and longitudinal edges of the frame. In such cases, preferably, end coverings 20 are provided, 50 which are usually in the form of sheets of paper of a sufficiently high grade to provide an attractive finish and appearance. These paper sheets are glued and applied in a manner sufficiently indicated in the drawing, so 55 as to cover end marginal portions of the sides and longitudinal edges of the envelope and the outer faces of the end frame members 11. These end areas 21 may, if desired, be imprinted with any suitable indicia, such as advertising matter or grade 60 marks to identify the fabric in some way, or else the end cover sheets may be entirely plain, and separate end labels may be applied by the textile manufacturers.

65 The complete article, as shown in Fig. 1,

is very stiff and rigid, being resistant to ordinary bending strains in any direction, and also to twisting strains. It is amply strong to properly hold and support any fabric which it is desired to wind upon it, 70 and as strong or stronger than the average wood frame board. It also has an attractive surface appearance or finish, and the envelope or cover is practically perfectly smooth and affords a proper surface for contact 75 with any fabric.

I claim:

1. A cloth board or frame comprising a frame composed of fibrous sheet material of substantial thickness and stiffness, and including originally independent tubular longitudinal side members, originally independent tubular transverse members in spaced relation secured to the side members. 80

2. A cloth board or similar article comprising a frame composed of fibrous sheet material of substantial thickness and stiffness, and including originally independent tubular longitudinal side members, originally independent tubular transverse members in spaced relation secured to the side members, and a cover of fibrous sheet material of moderate thickness adhesively secured to the frame and covering and concealing it, and affording a smooth surface to receive fabrics wound upon the board, the transverse members being of substantially polygonal cross section. 90

3. A cloth board or similar article comprising a frame composed of fibrous sheet material of substantial thickness and stiffness, and including originally independent tubular longitudinal side members, originally independent tubular transverse members in spaced relation secured to the side members, the transverse members being of polygonal cross-section and having their ends cut in arcuate form to fit segments of the side members. 100

4. A cloth board frame consisting of fibrous sheet material such as cardboard, and including cylindrical side members, at least one transverse tubular reenforcing member having its ends curved to fit about segments of the side members and secured thereto, tubular end members similarly formed and secured to the side members within the limits of end portions thereof, and stiff and strong end reenforcing and finishing pieces applied to the end surfaces of the end members and overlapping the ends of the side members and contoured to match them, these end reinforcements providing smooth, stiff surfaces to receive end labels. 115

5. A cloth board frame comprising side members shorter than the length of the frame, and end members, said members being of substantial cross section and being connected at their ends, the end members having end portions overlapping and entire- 125

ly covering the ends of the side members to resist inward displacement of the end members, the ends of said end portions being contoured in agreement with the adjacent longitudinal edge faces of the side members, and the end members also having smooth, flat outer faces, the length and width of which are equal to the full width and thickness of the frame providing uninterrupted surfaces

10 to support and maintain end labels in

smooth and undamaged condition, the end members adjacent said overlapping end portions having shoulders of substantial area fitting the inner contours of the end portions of the side members to brace the frame 15 against angular deformation.

Signed at New York city in the county of New York and State of New York this 17th day of February A. D. 1925.

GEORGE B. SCHEFFEY.
